UNITED STATES PATENT OFFICE.

STANLEY SMIGIELSKI, OF DETROIT, MICHIGAN.

WHIRLIGIG.

1,327,360.

Specification of Letters Patent.

Patented Jan. 6, 1920.

Application filed October 15, 1919. Serial No. 330,846.

To all whom it may concern:

Be it known that I, STANLEY SMIGIELSKI, a citizen of Poland, residing at Detroit, in the county of Wayne and State of Michigan, have invented certain new and useful Improvements in Whirligigs, of which the following is a specification.

The primary object of the present invention resides in the provision of a whirligig in the form of a rotatable element propelled by the wind with the rotary motion thereof communicated to a revolvably mounted disk upon which a pair of figures are supported.

Another object of the invention is to provide a whirligig in the form of a hand toy with a rotatable element driven by wind and having frictional contact with a rotatable disk, the rotatable member being adjustable on a carrying element to vary the speed of rotation of the driven disk.

With the above general objects in view and others that will become apparent as the nature of the invention is better understood, the same consists in the novel construction, combination and arrangement of parts hereinafter more fully described and then claimed, reference being had to the accompanying drawing by like characters designating corresponding parts throughout the several views, and in which,

Figure 1 is a side elevational view of a toy constructed in accordance with the present invention, parts thereof being shown in section,

Fig. 2 is a rear elevational view thereof with the toy figures removed from the rotating disk,

Fig. 3 is a cross sectional view taken on line III—III of Fig. 1, showing the journal bearing for the driving shaft,

Fig. 4 is a cross sectional view taken on line IV—IV of Fig. 1, showing the adjustable connection between the handle and the fan carrying bracket, and

Fig. 5 is a fragmentary elevational view of a modified form of the invention.

Referring more in detail to the accompanying drawing, there is illustrated a handle 5 by which the toy is grasped having a head 6 at its upper end with a vertically extending shank 7 extending upwardly of the head and being rectangular in cross section as shown in Figs. 3 and 4. A disk or turn table 8 is revolvably supported as at 9 upon the disk 8 and carries toy figures 10

embracing each other in simulation of a dance.

A bracket is carried by the handle 5 and includes a shank 11 bifurcated as at one end to provide furcations 12 positioned at opposite sides of the handle shank 7 and having longitudinal slots 13 therein through which a screw 14 transversely passes for engagement in the shank 7 and retained by the thumb nut 15. The opposite end of the bracket shank 11 is upwardly curved as indicated in Fig. 1 with a horizontal bearing 16 at the end thereof, an arm 17 being carried by the shank 11 intermediate the bearing 16 and the handle shank 7 and having a bearing in the upper end thereof alined with the bearing 16 and in which bearings a shaft 18 is journaled, the shaft 18 slidably extending through an opening 19 provided in the handle shank 7 while the opposite end 75 of the shaft carries a fan wheel 20. A friction wheel 21 is secured to the shaft 18 at a point adjacent the bracket arm 17, being rotatable with the shaft and frictionally engaging the bottom face of the toy support- 80 ing disk 8.

Assuming the device to be in the position shown in Fig. 1 with the handle 5 grasped by the hand, and holding the fan 20 in position for direct contact by wind or other 85 gusts of air, the fan is rotated and being fixed to the shaft 18 rotates the shaft and in turn the friction disk 21, which being in mesh with the bottom face of the disk 8 rotates the disk. The device may be carried by a child and operated during forward running of the child or the device may be mounted upon a suitable support with the fan blade facing the wind. Should it be desired to regulate the speed with 90 which the disk 8 is caused to rotate, the thumb nut 15 upon the screw 14 extending transversely of the handle shank 7 is loosened to permit the sliding of the forked end 13 of the bracket shank 11 to 100 position the friction disk 21 at a point nearer the central axis of the disk 8.

While there is herein shown and described the preferred embodiment of the invention, it is to be understood that minor changes 105 may be made in the details of construction as will fall within the scope of the invention set forth in the subject matter herein-after claimed.

A modified form of the invention is shown 110

in Fig. 5 and embodies the essential details thereof with the exception that the framework of the device is formed of twisted wire as illustrated at 5' constituting the handle portion while the strands are separated with one strand bent at an angle to form a bracket 11' having bearings 16' and 17' for the fan shaft 18'. A revolving disk 8' is journaled upon the upper end of a support 7' secured to the upper bearing 17' and immovably carried thereby while a friction disk 21' secured to said shaft between the bearings 16' and 17' engages the lower face of the disk 8' to rotate the same. The shaft 18' receives its power from a fan wheel designated by the reference numeral 20 shown in the preferred form of the invention and the friction disk 21' rotates the disk 8' in an obvious manner, the shaft 18' being slidable in the bearings above noted for purposes of varying the speed of rotation of the disk 8'.

What is claimed as new is:—

1. A device of the class described comprising a handle, a shank carried thereby, a bracket having a forked end inclosing the shank of said handle, a fan journaled in said bracket, a disk rotatable upon said

handle shank, figure toys upon said disk, and means for communicating motion from the fan to the disk.

2. A device of the class described comprising a handle, a shank carried thereby, a bracket having a forked end inclosing the shank of said handle, a fan journaled in said bracket, a disk rotatable upon said handle shank, figure toys upon said disk, means for communicating motion from the fan to the disk, said means including a shaft driven by said fan, and a friction disk upon said shaft in engagement with the lower face of the disk upon the handle shank.

3. A device of the class described comprising a handle, a shank carried thereby, a bracket having a forked end inclosing the shank of said handle, a fan journaled in said bracket, a disk rotatable upon said handle shank, figure toys upon said disk, means for communicating motion from the fan to the disk, and pin and slot connections between the handle shank and bracket fork for changing the position of the bracket on the handle.

In testimony whereof I affix my signature.

STANLEY SMIGIELSKI.
